UNITED STATES PATENT OFFICE.

FREMONT P. LIVINGSTON, OF DENVER, COLORADO.

DESIGN FOR A FOOT-MAT FRAME FOR AUTOMOBILES.

58,606.

Specification for Design.

Patented Aug. 2, 1921.

Application filed October 13, 1920. Serial No. 416,765. Term of patent 14 years.

To all whom it may concern:

Be it known that I, FREMONT P. LIVINGSTON, a citizen of the United States, residing at Denver, in the county of Denver and State of Colorado, have invented a new original, and ornamental Design for Foot-Mat Frames for Automobiles, of which the following is a specification, reference being had to the accompanying drawing, forming part thereof.

The figure of the drawings is a perspective view of a foot mat frame for automobiles, showing my new design.

I claim—

The original design for a foot mat frame for automobiles, as shown.

FREMONT P. LIVINGSTON.
